HOLDER FOR POT COVERS OR THE LIKE

Elmer E. Johnson, Sausalito, Calif.

Application April 3, 1950, Serial No. 153,665

2 Claims. (Cl. 248—293)

1

This invention relates to a device for holding a pot cover or similar article.

Summarizing the invention, the device comprises a bracket member adapted to be secured to a supporting surface, a holder element pivotally mounted on the bracket member, and resilient means which urges the holder element toward the surface so that the pot cover is held between the holder element and the surface. The holder element is forked to accommodate the cover. Objects of the invention are to provide an arrangement of the type described which will enable the cover to be held in otherwise unused space such as under a shelf or on the back of a cabinet door, which will protect the cover from becoming dented, and which is of simple and economical construction. Other objects will become apparent from a perusal of the following description of the invention.

Referring to the drawings:

Fig. 1 is an isometric view of the holder and a pot cover which it is adapted to hold;

Fig. 2 is a sectional side elevation of the holder and a pot cover held by the holder against the underside of a cabinet shelf;

Fig. 3 is a similar view showing a cover held against a vertical wall; the position which the holder element has before the cover is positioned thereon being shown in dotted lines;

Fig. 4 is a vertical sectional view through the holder;

Fig. 5 is a sectional elevation taken in a plane indicated by line 5—5 in Fig. 4.

The device comprises a bracket member 2 and a holder element 3. Bracket 2 is formed of a metal stamping having a planar base portion 4, a flange 6 at one end and side flanges 7 which extend to a position adjacent the opposite end 8 of the base portion. The opposite ends of flange 6 are formed as ears 9 having apertures therein for receiving screws 11 adapted to provide means for securing the device to any suitable supporting surface.

Means is provided adjacent end 8 of the bracket opposite to the securing flange end 6, to pivotally connect holder element to the bracket member. Such means comprises a pivot pin 12 which is secured in triangularly shaped side flanges 13 formed on a metal plate 14 providing the base of holder element 3. Pin 12 is pivoted in apertures in side flanges 7; and spring means is provided for continually urging the holder element to a position toward the securing flange 6 of the bracket member so that the holder element is continually urged toward the surface on which the device is secured.

2

Such spring means may be of any suitable construction, but preferably comprises a spring element having end coils 16 about pivot pin 12, a central portion 17 engaging an inturned lug 18 at the bracket end of plate 14, and straight ends 19 engaging base portion 4 of the bracket. By pivotal connection of the holder element to the bracket member at the described location, the end 8 of the bracket member provides a stop for limiting the direction of pivotal movement of the holder element toward the securing end of the bracket or in other words, the surface to which the bracket is secured. Also, it will be noted that such stop causes the holder element to make an acute angle with respect to the bracket member for a purpose to be subsequently explained.

The remainder of the holder element comprises a pair of metal arms or prongs 21 which form a forked structure to accommodate the handle and the usual curvature of a pot cover 20; the arms or prongs comprising inner spaced portions 22 which are suitably secured to plate 14 of the holder element by any suitable means such as spot welding, and portions 23 which diverge outwardly from adjacent the bracket member. The outwardly diverging character of these prongs facilitates entrance of the pot cover between the prongs, and also accommodation of the usual curvature of the cover. The outer portions 24 of outwardly diverging portions 23 are angularly disposed outwardly to provide a more or less cam surface for facilitating reception of the cover.

The holder may be mounted at any suitable location. For example, as illustrated in Fig. 2, it may be conveniently attached underneath a shelf 26 fastened to a wall 27. As shown in Fig. 3, it may be mounted on a vertical wall surface 28 which may be the inside of a cabinet door or may be an outside wall. In this connection, to conserve space, the holder may be mounted in angular position with reference to vertical instead of a vertical position as shown.

Because of the resilient pressing of the holder element toward the surface upon which the device is supported, the pot cover will be firmly held or clamped between the holder element of the device and the wall surface, thereby obviating rattling. At the same time, since the stop edge 8 limits the position of the holder element resulting from thrust of the resilient means, as shown by the dotted line position in Fig. 3, an opening will prevail at the end of the holder element at which the cover is inserted, to facilitate reception of the cover. This is also facilitated by the angular disposition of the outer end portions 24 of the holder element prongs.

The fixed acute angle positioning of the holder element with respect to the bracket member, obtained by virtue of the stop edge 8 against which the holder element abuts when it is not holding a cover, insures sufficient space for reception of the cover. Also, such stop maintains the holder element in a fixed position when the device is attached to the supporting surface, so as to facilitate attachment thereof without interference from parts which might otherwise move.

I claim:

1. A holder for a pot cover or the like comprising a bracket member having a base portion, means adjacent one end of said base portion adapted to be secured to a supporting surface with said base portion projecting perpendicular from said surface, a holder element extending always in substantially the same direction as said surface; means pivotally mounting said holder element adjacent the opposite end of said base portion with said holder element projecting transversely with respect to said base portion, said opposite end of said base portion forming a stop to limit movement of said holder element toward said one end of said base portion with the free end of said holder element positioned inwardly of said one end of said base portion whereby a space is provided between the free end of said holder element and said surface for reception of said cover; said holder element comprising a pair of prongs diverging outwardly from adjacent said bracket member, the outer end portions of said prongs having an opening therebetween and being angularly disposed outwardly from the plane in which the inner portions of said prongs lie to facilitate reception of said cover; and spring means between said bracket member and said holder element for urging said holder element toward said surface and said stop whereby the cover is adapted to be held between said surface and said holder element.

2. A holder for a pot cover or the like consisting essentially of a bracket member and a holder element, said bracket member comprising a substantially flat base portion having flange means adjacent one end thereof adapted to be secured to a supporting surface with said base portion perpendicular to said surface, said holder element extending always in substantially the same direction as said surface, means pivotally mounting said holder element adjacent the opposite end of said base portion with said holder element projecting always transversely with respect to said base portion, said opposite end of said base portion forming a stop to limit movement of said holder element toward the end of said base portion provided with said flange means, and spring means between said bracket member and said holder element urging said holder element always toward said surface and said stop, said holder element comprising a pair of prongs diverging outwardly from adjacent said pivotal mounting means whereby the cover can be accommodated between said prongs and held between said surface and said prongs.
